UNITED STATES PATENT OFFICE.

HENRY D'OLIER, JR., OF PHILADELPHIA, PENNSYLVANIA.

BALANCED CORD-DROP ATTACHMENT.

SPECIFICATION forming part of Letters Patent No. 766,800, dated August 2, 1904.

Application filed March 4, 1904. Serial No. 196,583. (No model.)

To all whom it may concern:

Be it known that I, HENRY D'OLIER, Jr., a citizen of the United States, residing at Philadelphia, in the county of Philadelphia and 5 State of Pennsylvania, have invented a new and useful Balanced Cord-Drop Attachment, of which the following is a specification.

My invention relates to incandescent-lamp attachments, more particularly such as will 10 permit of the employment of an ordinary incandescent lamp in such position that its longitudinal axis may be maintained horizontal even in the case where the lamp is to be suspended by the usual drop-cord.

15 A further feature of my invention is an arrangement whereby the incandescent lamp when thus held in a horizontal position may be rotated to any position about the drop-cord or other support as an axis and whereby the 20 lamp may be caused to take any desired position and be independent of the twisting effects or tendencies of the cord and whereby electrical communication is maintained between the lamp and cord or fixture irrespective of 25 position of the lamp.

A further feature of my invention is the 30 balancing of the entire lamp and fixture, so that the lamp will extend practically horizontally or in an inclined position and be independent of the usual string resorted to for 35 tying up a cord-suspended lamp into a horizontal position.

A further feature of my invention is the 40 means whereby the lamp is made portable and stable in upright position.

In many places it is essential that the incandescent lamps be suspended by their own conducting-cord, the practice heretofore being 45 to permit the lamp to hang with its axis vertical and practically coincident with the axis of the cord. It is a fact that an incandescent lamp so supported sheds the greater part of its light in horizontal directions, and the amount of light radiated vertically downward 50 below the lamp is greatly less than the illumination in a horizontal direction. By actual tests with numerous incandescent lamps I have found that with the axis of the lamp vertical the intensity of the illumination in a horizon-

tal direction may be expressed, for example, 50 by sixteen-candle power. At the same time, however, the illumination in a direction vertically below the lamp is represented by 7.9 candle-power. In other words, the illumination directly below the lamp is only one-half 55 of what it is in the horizontal direction. In factories, machine-shops, and the like the workmen appreciate the fact that a lamp hung directly above their machine or work does not when in the ordinary vertical position shed 60 the most light downwardly. In consequence the workman will tie his lamp up with a string extending between the lamp and some portion of the cord, so as to hold the lamp in an approximately horizontal position. He is then 65 instantly met with the difficulty that the cord will twist and turn the lamp to a position which he does not desire. It is to overcome such difficulties that my invention is well adapted—that is, to provide an attachment 70 whereby the lamp will be held in an approximately horizontal position and be capable of rotation to any position independently of its cord or other support and also be independent of the position of the attachment itself in its 75 socket.

Reference is to be had to the accompanying drawings, in which—

Figure 1 is a top plan view of a lamp and its attachment, the attachment-plug being 80 omitted. Fig. 2 is a side view, partly in section, of the lamp and attachment. Fig. 3 is a view of the under side of the attachment-plug portion. Fig. 4 is a plan view of a similar double lamp attachment. Fig. 5 is a side 85 view, partly in section, of the double lamp attachment.

Referring to the drawings, 1 represents the screw-threaded brass shell of an attachment-plug as adapted to screw into an ordinary 90 Edison lamp-socket S, suspended by a lamp-cord C or suitable fixture. As well understood, this screw-threaded shell forms one terminal of the circuit. The other terminal is the metallic button 2, held on the mass 3, of 95 insulating material. The metallic screw-threaded shell 1 is held between the insulating material 3 and the insulating head mem-

ber 4 by the axially-extending metallic screw 5, whose head engages in a countersink in the metal button 2 and whose lower screw-threaded end engages in a contact to be described 5 hereinafter.

6 is a metallic piece soldered or riveted to the metallic shell member 1 and engaged by a screw 7, extending through a perforation in the head member 4. Beneath the head of the 10 screw 7 and held between it and the bottom of the depression 8 of the head member 4 is a brush-contact 9, made of suitable resilient conducting material. The rim or partition 10 extends eccentrically across the bottom of the 15 head member 4, and thus divides the cavity in the end of this head member into the two depressed portions 8 and 11.

A rectangular channel 12 is formed in the head member 4, and in this channel engages 20 the flange 13, forming a part of the spun-metal casing 14, having a general spherical shape. Within the casing 14 is held a porcelain member 15, having an annular depression 16, in which is held the metallic ring 17, 25 having the downwardly-extending tongue 18, held in a depression in the porcelain member 15. Engaging the tongue 18 is a screw, rivet, or other suitable means whereby the screw-threaded socket-contact 19 is put in electrical 30 communication with the ring 17 and also held mechanically in fixed position with regard to the porcelain member 15. A similar bolt 20 also serves to hold the shell 19 to the downwardly-extending portion 15' of the porcelain 35 member 15. Through the opening 21 in the extension 15' extends the metallic contact-piece 22, which is tapped to receive the lower end of the screw 5 and is held fixed to said screw 5 by means of the check-nut 23. After 40 passing through the opening 21 the contact 22 is bent downwardly and forms the central contact of an ordinary Edison socket.

24 is the usual insulating-bushing between the screw shell-contact and the neck 25 of the 45 casing 14. This neck 25 has a bead 26 spun in it, this bead being embraced by the resilient fingers or clasps 27, formed on the reflector 28, having the opening 29, through which extends the incandescent lamp 30, having fil- 50 ament a.

31 is the screw-threaded contact, and 32 is the button-contact of the lamp 30, which engage, respectively, with the shell 19 and the contact 22.

55 The path of the current may be traced as follows: The current is received at the disk 2 from the central contact of an ordinary socket secured to and suspended by the usual lamp-cord. The current is then conducted by the 60 screw 5 to the contact 22, thence to the button-contact 32 of the lamp 30, through the lamp to the screw-threaded base 31, thence to the shell 19, through the tongue 18 to the ring 17, through the brush-contact 9 to the 65 screw 7, to the metallic piece 6, to the screw-

threaded shell 1, to the screw-threaded shell-contact of the socket.

The attachment-plug, having the member 1, is screwed into the usual incandescent-lamp socket, suspended by the usual cord drop. The 70 incandescent lamp is screwed into shell 19, and thus placed in communication with the conductors of the cord drop.

The attachment-plug and the parts within the spherical casing 14 are movable with respect to each other, and in consequence the shell member 14, lamp 30, and reflector 28 may be rotated to any position in the horizontal plane about the lamp-cord or screw 5 as an axis. This is made possible by the channel 12 and the engaging flange 13. Further, by the rotation of the head of the screw 5 within the countersink of the button 2 and by the engagement of the brush-contact 9 with the ring 17 to whatever position the lamp 85 30 may be rotated the brush 9 is always in contact with the ring 17 and the screw 5 with the button 2. From this construction it is apparent that an ordinary incandescent lamp may be suspended by a usual cord in a horizontal position and be capable of rotation to any position about the cord drop or fixture 90 as an axis. For example, the device shown in Fig. 2 may be screwed into an ordinary socket 95 as held by the lamp cord or fixture, the result being the horizontal extension of the lamp and its capacity to be rotated to any position. This latter feature is desirable, so that the position of the lamp 30 shall be independent of the position of the screw-threaded member 1 100 with regard to the socket which receives it and to be independent of the twist or set in the cord drop.

33 is a mass of lead or other suitable material held within the casing 14 in that portion 105 opposite the lamp 30. This weight then causes the center of gravity of the system to be coincident with the axis of the cord drop or fixture and results in the lamp 30 taking a horizontal position.

110 From the foregoing description it will be seen that I have provided a balanced rotary cord-drop attachment for holding an incandescent lamp in an approximately horizontal position, thus overcoming the difficulties encountered when simply suspending an incandescent lamp in a vertical position by a cord drop.

115 At 34 is shown a boss in the spun-metal casing 14, serving as a flat base upon which to stand the entire lamp and attachment to operate as a portable lamp, if desired, and which shall cause the axis of the lamp to extend vertically.

120 In Figs. 4 and 5 two oppositely-extending lamps are employed, which balance each other and render the lead balancing as shown in Fig. 2 unnecessary. The reference characters of Figs. 4 and 5 refer to the same parts similarly designated in Figs. 1, 2, and 3. It 125 130

is apparent that more than two lamps can be thus employed, they being so arranged as to produce a balanced system.

It is to be understood also that my invention is readily adaptable to the cases where the lamp is to be suspended and held in any position other than truly horizontal, any other inclination obviously being possible. It is to be understood also that my invention is not limited to the form in which Edison sockets are used, but that Thomson-Houston, Westinghouse, or any other socket may be employed with equal facility.

What I claim is—

- 15 1. In combination, an attachment-plug, a member secured thereto and rotatable relatively thereto, and a lamp-socket in said member, the axis of said lamp-socket being at an angle with the axis of said attachment-plug.
- 20 2. In combination, an attachment-plug, a member secured thereto, and capable of rotation with respect thereto, a lamp-socket carried by said member, the axis of said lamp-socket being at an angle with the axis of said attachment-plug, and means for maintaining electrical communication between the lamp-socket contacts and the contacts of said attachment-plugs.
- 25 3. In combination, an attachment-plug, a member secured thereto and capable of rotation with respect thereto, a lamp-socket and lamp carried by said member, the axis of said lamp being at an angle with the axis of said attachment-plug, means for maintaining electrical communication between the lamp-terminals and the terminals of the attachment-plug, and a weight for balancing the lamp.
- 30 4. In combination, an attachment-plug, a member coöperating therewith, a lamp supported by said member, and a counterweight for balancing said lamp and member about the axis of the attachment-plug.
- 35 5. In combination, an attachment-plug, a member coöperating therewith, a lamp supported by said member, and a counterweight for determining the position of said lamp.
- 40 6. In combination, a cord drop, an attachment-plug secured thereto, a lamp secured to said attachment-plug, the axis of the lamp being at an angle with the axis of the cord drop, and a counterweight for determining the position of the lamp.
- 45 7. In combination, an attachment-plug, a member coöperating therewith, a lamp-socket secured to said member, a casing embracing said member and socket and engaging with said attachment-plug, and means for maintaining electrical communication between said attachment-plug and said lamp-socket.
- 50 8. In combination, an attachment-plug, a member rotatable with respect thereto, a lamp-socket supported by said member, and a casing inclosing said member and socket and serving to maintain said member in operative relationship with said attachment-plug.

9. In combination, an attachment-plug, a member rotatable with respect thereto, a lamp-socket supported by said member, a casing inclosing said member and lamp-socket and serving to maintain said member in operative relationship with respect to said attachment-plug, and means for maintaining electrical communication between said attachment-plug and said lamp-socket.

10. In combination, an attachment-plug, a member coöperating therewith, a lamp-socket secured to said member, a counterweight, and a casing inclosing said member, lamp-socket and counterweight.

11. In combination, an attachment-plug, a member coöperating therewith, a lamp-socket secured to said member, a casing inclosing said member and lamp-socket, and a reflector secured to and rotatable on said casing.

12. In combination, an attachment-plug, a member coöperating therewith, a lamp supported by said member, the axis of said lamp being at approximately right angles with the axis of said attachment-plug, a casing inclosing said member, and a reflector supported by said casing.

13. In combination, an attachment-plug, a member coöperating therewith, a lamp system supported by said member, the axis of the lamp being at approximately right angles with the axis of the attachment-plug, and a weight for balancing said lamp system about the axis of the attachment-plug.

14. In combination, an attachment-plug, a member coöperating therewith, a lamp system supported by said member, the axis of the lamp being at approximately right angles with the axis of said attachment-plug, a weight for balancing said lamp system about the axis of said attachment-plug, and a casing inclosing said member and weight.

15. In combination, an attachment-plug, a member coöperating therewith and rotatable with respect thereto, a lamp system supported by said member, means for maintaining electrical communication between said attachment-plug and the lamp, and a weight for balancing said lamp system about the axis of the attachment-plug.

16. In combination, an attachment-plug, a member coöperating therewith and rotatable with respect thereto, the axis of the lamp being at approximately right angles with the axis of said plug, means for maintaining electrical communication between said attachment-plug and said lamp, and a weight for balancing said lamp system about the axis of the attachment-plug.

17. In combination, an attachment-plug, a member coöperating therewith and rotatable with respect thereto, a lamp system supported by said member, the axis of the lamp being at approximately right angles with the axis of the attachment-plug, means for maintaining electrical communication between said attach-

- ment-plug and said lamp, a weight for balancing said lamp system about the axis of said attachment-plug, and a casing inclosing said member and weight.
18. In combination, a cord drop, an attachment-plug supported thereby and in electrical communication therewith, a member secured to and rotatable with respect to said attachment-plug, a lamp supported by said member, means for maintaining electrical communication between said lamp and said attachment-plug, and a weight for balancing said lamp in approximately horizontal position.
19. In combination, a cord drop, an attachment-plug supported thereby and in electrical communication therewith, a member secured to and rotatable with respect to said attachment-plug, a lamp supported by said member, means for maintaining electric communication between said lamp and said attachment-plug, a weight for balancing said lamp in approximately horizontal position, and a casing inclosing said member and weight.
20. In combination, a cord drop, a lamp-socket supported thereby, a member engaging in said lamp-socket, a second lamp-socket secured to said member and having its axis at an angle with the axis of said cord drop, means for rotating said second lamp-socket about said cord drop to any desired position, and 30 means for maintaining electrical communication between said second lamp-socket and said cord drop.
21. In combination, a cord drop, a lamp-socket secured thereto, an attachment-plug 35 engaging in said lamp-socket, the axes of said lamp-socket and attachment-plug approximately coinciding with the axis of the cord drop, a member supported by said attachment-plug, a lamp supported by said member, and 40 a weight for balancing said lamp, whereby its axis is at an angle with the axis of said cord drop.
22. In combination, an attachment-plug, a lamp supported thereby and rotatable with 45 respect thereto, and a shade rotatable with respect to the said lamp.
23. In combination, an attachment-plug, a casing rotatable with respect thereto, a lamp rotatable with said casing and having its axis 50 approximately at right angles with the axis of said attachment-plug, and a shade rotatable with respect to said casing.
